ARRANGEMENT FOR PRODUCING ELECTRICAL OSCILLATIONS.

1,061,717.

Specification of Letters Patent.

Patented May 13, 1913.

Application filed April 11, 1911. Serial No. 620,496.

To all whom it may concern:

Be it known that I, GEORG GRAF VON ARCO, a subject of the German Emperor, and residing at Berlin, Germany, have invented 5 a certain new and useful Improved Arrangement for Producing Electrical Oscillations, of which the following is a specification.

My invention relates to an arrangement for producing electrical oscillations by direct 10 current.

The use of direct current as compared with alternating current has very great advantages, more particularly for small installations, but arrangements of this kind 15 hitherto employed have not worked satisfactorily by reason of the greater sparking at the interrupter, more particularly in the case of a high frequency of interruption and where high potentials are used.

Now by the present invention sparking is substantially avoided by using a transformer for increasing the potential, the leakage of the transformer being smaller than that of an ordinary induction coil; for instance I 25 may use a transformer with a closed magnetic circuit and without a series choking coil, and a spark gap having an extinguishing effect in the primary oscillation circuit, such as for instance a Wien spark gap or a 30 Rendahl mercury vapor lamp. The forming of sparks is further suppressed by a peculiar construction of the interrupter which will be hereinafter more particularly described.

Several forms in which the invention may 35 be reduced to practice are shown in the accompanying drawings, in which:—

Figure 1 is a diagram of the entire electrical arrangement. Figs. 2 and 3 are side and end views respectively of one form of 40 interrupter, and Fig. 4 shows another form of interrupter construction.

The feeding circuit consists of a direct current generator 1, an interrupter 2, an ordinary condenser 3 inserted in parallel 45 thereto, and a transformer 4 with a closed magnetic circuit; the primary oscillation circuit (extinguishing circuit) consists of a condenser 5, an extinguishing spark gap 6 and a coupling coil 7, while the secondary oscillation circuit is formed of an aerial wire 8 connected to earth and a coupling coil 9.

Owing to the spark gap having a sudden extinguishing action, the whole energy set in motion when a spark passes over the

spark gap is immediately transmitted in the 55 ordinary way to the secondary circuit, so that after the extinguishing of the spark gap the condenser 5 is practically entirely discharged. The closed magnetic circuit transformer therefore affords the advantage on account of its very small leakage of introducing only a very slight self induction in the 60 feeding circuit.

As the interrupter, which is diagrammatically represented at 2 in Fig. 1, a disk circuit breaker 10 (Figs. 2 and 3) made like a commutator is preferably employed, which is mounted on a shaft 21 rotated at the proper speed by suitable means (not shown). This disk has, arranged as usual, a suitable 65 number of current conducting bars. Slip rings 11, 11' and 11'' are mounted on shaft 21 and insulated therefrom near the interrupter disk and each ring is connected with certain of the interrupter bars by means of 70 wires 12 in alternate sequence with the other ring. For instance one ring with the first, fourth and seventh bar, the second ring with the second, fifth, eighth and so-forth, and the third ring with the third, sixth, ninth 75 and so-forth. Only one of the three rings shown, *i. e.* ring 11'' as shown in Fig. 2, is connected with the dynamo in a circuit of the character shown in Fig. 1, while the others serve as reserve, for instance, in case 80 one of the bars connected with slip ring 11'' has become defective. Fig. 2 clearly shows how any of the three rings may be connected in circuit with the dynamo by having for instance brush 14 of the interrupter 10 directly 85 connected with the dynamo 1. The brushes 21, 22 and 13 of the slip rings are connected to contacts 16, 17 and 18 respectively of a selective switch 20, the lever 15 of which is 90 in turn connected with the dynamo circuit, 95 so that by setting the lever on any of its contacts, any of the slip rings may be thrown into the circuit. When during rotation of the interrupter, and with the switch position for instance as shown in Fig. 2, brush 14 100 contacts with bars which are connected with the wires 12 leading to any of the two slip rings 11 and 11', the circuit is opened and it is only closed for the time in which the brush contacts with bars which are in direct 105 connection by means of a wire 12 with the slip ring 11''. This arrangement gives therefore a proportion of 2 : 1 for the time

the circuit is open to the time the circuit is closed. As experiments have shown, a further diminution of sparking is produced thereby. However, where high potential is employed in order to reduce the formation of an arc and to prolong the life of the apparatus, it has been found very advantageous to employ a plurality of interrupter disks connected in series instead of one disk. It is, however, essential that they rotate synchronously or almost synchronously, so that the interruptions take place simultaneously. Only a portion of the total potential then exists between two contracting elements, so that with a suitable number of interrupters connected in series a current of any suitably high potential may be interrupted without damage to the contacts. Fig. 4 shows a way of carrying out this idea. Each interrupter disk 10 is provided with a slip ring 11. The current is led to the bars by means of brushes 14 and it is taken away by brushes 13 in contact with rings 11. Both interrupters are connected in series in such a way that the passage of current from the brushes 14 to the respective interrupter bars takes place in the same direction in both interrupters, so that all the brushes on the one hand and the bars on the other hand have the same polarity. By this means an unequal burning away of the brushes is prevented. Now it has also been found that with a certain connection of the two interrupter electrodes, namely the bars and the brushes the bars are more rapidly destroyed than the brushes and that vice versa if the connections are reversed, the brushes burn away more rapidly, but the bars remain effective for a considerably longer time if the brushes are employed as anode. Accordingly the invention further consists in selecting such a polarity that of the two electrodes the brushes burn away more rapidly. Finally it has also been found that a particularly favorable action of the apparatus is obtained if the brushes are made of silver. This is probably due to the fact that silver is a very good conductor of heat, that it is soft and that it causes the smallest arc.

I claim:

1. In an arrangement for producing electric oscillations by interrupted direct current, a feeding circuit containing in series a direct current source, an interrupter, the primary coil of a transformer having a closed magnetic circuit, a primary oscillation circuit containing a quench spark gap and a capacity adapted to be loaded by the secondary coil of the transformer, and a slightly damped secondary oscillation circuit closely coupled with the primary circuit.
2. In an arrangement for producing electric oscillations by interrupted direct cur-

rent, a feeding circuit containing in series a direct current source and a rotatable interrupter comprising a suitable number of current conducting bars, a slip ring electrically connected with some of said bars to cause the periods of "open circuit" to be larger than the periods of "closed circuit" in the interruptions of the feed current, a transformer having a closed magnetic circuit and having its primary coil in series with said circuit, a primary oscillation circuit containing a quench spark gap and a capacity adapted to be loaded by the secondary coil of said transformer, and a slightly damped secondary oscillation circuit closely coupled with the primary circuit.

3. In an arrangement for producing electric oscillations by interrupted direct current, a feeding circuit containing in series a direct current source and a rotatable interrupter comprising a suitable number of current conducting bars, a plurality of slip rings, each ring being electrically connected with an equal number of bars in alternate sequence with the bars connected to the other rings, a brush sliding on the interrupter bars, a brush for each of said slip rings, a connection between the interrupter brush and one pole of said source, means for connecting any of said slip ring brushes with the other pole of said source, a transformer having a closed magnetic circuit and having its primary coil in series with said source, a primary oscillation circuit containing a quench spark gap and a capacity adapted to be loaded by the secondary coil of the transformer, and a slightly damped secondary oscillation circuit closely coupled with the primary circuit.

4. In an arrangement for producing electric oscillations by interrupted direct current, a feeding circuit containing in series a direct current source and a plurality of disk interrupters, each disk having a brush coöperating with it and a slip ring connected to it, and a brush coöperating with said ring, said disks adapted to interrupt the current substantially synchronously and so connected that the current passes between the disk brush and the interrupter disk in the same direction in all interrupters, a transformer having a closed magnetic circuit, and having its primary coil in series with said current source, a primary oscillation circuit containing a quench spark gap and a capacity adapted to be loaded by the secondary coil of the transformer, and a slightly damped secondary oscillation circuit closely coupled with the primary circuit.

5. In an arrangement for producing electric oscillations by interrupted direct current, a feeding circuit containing in series a direct current source, and a rotatable in-

5 interrupter comprising a disk having a plurality of current conducting bars, a slip ring electrically connected with some of the bars, a brush sliding on the interrupter
 10 disk, another brush sliding on the slip ring, the polarity between the interrupter disk and its brush being suitably selected to cause the brush sliding on the disk to burn away more rapidly than the bars, a transformer
 15 having a closed magnetic circuit, and having its primary coil in series with said current source, a primary oscillation circuit containing a quench spark gap and a capacity adapted to be loaded by the secondary coil
 20 of the transformer, and a slightly damped secondary oscillation circuit closely coupled with the primary circuit.

6. In an arrangement for producing electric oscillations by interrupted direct current, a feeding circuit containing in series
 25 a direct current source, and a rotatable

interrupter comprising a disk having a plurality of current conducting bars, a slip ring electrically connected with some of the bars, a brush sliding on the disk, said brush 25 consisting of silver, another brush sliding on the slip ring, said two brushes being connected in series with the current generator, a transformer having a closed magnetic circuit and having its primary coil in series 30 with said source, a primary oscillation circuit containing a quench spark gap and a capacity adapted to be loaded by the secondary coil as a transformer, and a slightly damped secondary oscillation circuit closely 35 coupled with the primary circuit.

In testimony whereof, I affix my signature in the presence of two witnesses.
